DESIGN FOR A COAT

Samuel Zimmerman, New York, N. Y.

Application February 7, 1939, Serial No. 82,830

Term of patent 3½ years

To all whom it may concern:

Be it known that I, Samuel Zimmerman, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein

The characteristic feature of my design resides in the combination on the coat disclosed of the specific curved breast pockets in association with the upward and outwardly matching curves extending to the shoulders, as shown.

I claim:

The ornamental design for a coat, substantially as shown and described.

SAMUEL ZIMMERMAN.
